United States Patent Office

Des. 195,359
Patented June 4, 1963

195,359

CALIPER RULER

Alfred Robbins, 55 Central Park W., New York, N.Y.

Filed Mar. 23, 1962, Ser. No. 69,395

Term of patent 14 years

(Cl. D52—6)

Fig. 1

Fig. 2

Fig. 3

FIG. 1 is a top plan view of the caliper ruler showing my new design;

FIG. 2 is a bottom plan view of the caliper ruler;

FIG. 3 is a side elevational view of the caliper ruler. The essential features of the design reside in the portions shown in solid lines.

I claim:

The ornamental design for a caliper ruler, substantially as shown and described.
